SAFETY SCISSORS

Louis J. Schnitzer, Chicago, Ill., assignor to Inland Engineering, Inc., Chicago, Ill., a corporation of Illinois

Application April 11, 1958, Serial No. 50,433

Term of patent 14 years

(Cl. D22—5)

Fig. 1 is a side elevational view of the safety scissors showing my new design;

Fig. 2 is a top edge view thereof;

Fig. 3 is an elevational view showing the side opposite Fig. 1;

Fig. 4 is a top edge view of the safety scissors shown in Fig. 3;

Fig. 5 is an end elevational view looking in the direction of the arrows 5—5 in Fig. 1;

Fig. 6 is an end elevational view looking in the direction of the arrows 6—6 in Fig. 1; and

Fig. 7 is a side elevational view similar to that of Fig. 1 as it appears with parts of the shield and handles broken away and showing the cutting blade in cutting position.

The essential feature of the design resides in the cutting head consisting of the cutting blade and shield, as shown.

I claim:

The ornamental design for safety scissors, as shown and described.
